DOUBLE ACTING SERVOMOTOR

Francis W. Davis, Belmont, Mass.

Application April 10, 1933, Serial No. 665,329

6 Claims. (Cl. 121—41)

30 For a more complete understanding of this invention reference may be had to the description thereof which follows and to the drawing of which.

Figure 1 is a longitudinal sectional view of a servo-motor embodying the invention.

Figure 2 is a sectional view of the forward end of the motor, taken on the line 2—2 of Figure 1.

Figure 3 is a fragmentary sectional view of the rear end of the apparatus shown in Figure 1. Figure 4 is a diagrammatic representation of several parts of an automobile, showing how the invention may be employed.

40 Within which is slidably fitted a valve member 50. The forward portion of the valve member is hollow as at 51, the rear end of the valve member projecting from the rear end of the piston rod 41 and terminating in a yoke 52 which

Figures 5 and 6 are fragmentary portions of Figure 1, showing the parts in different relative positions of operation.

the interior of the stem through a series of holes 61. The groove 60 opens into the chamber 35 when the piston is in its extreme rearward position as shown in Figure 1. Thus oil entering the 5 inlet 20 normally flows through the chamber 36 into the interior of the stem 46, through the holes 61 and the groove 60 into the main chamber 35, and thence outwardly through the outlet 21. Since these passages offer a relatively unrestrictive flow for the oil through the casing, there is but little oil pressure ordinarily in the casing. It may be noted that such pressure as there may be at times in the chamber 36 acts against the valve member 50, tending to assist the spring 57 10 in pressing the valve member rearwardly. Oil pressure in the chamber 36 also acts against the forward end of the stem 46, the effective area of pressure being equal to the annular area of cross section of this stem. For the operation of the 15 motor, the valve element 50 is provided with a pair of external annular grooves 65 and 66, these grooves being separated by an annular rib 67. The groove 65 is in constant communication with the interior hollow 51 by a series of holes 68 20 through the wall of the valve member 50. Opposite this rib 67 is an annular groove 70 in the inner wall of the piston rod 41 and stem 46, the groove 70 communicating through a series of holes 71 with a pressure chamber 75 in the casing 25 30, rearward of the piston 40. The groove 66 communicates with the chamber 35 forward of the piston as by a number of holes 76. As shown in Figure 1, the groove 65 in the valve is normally cut off from communication with the groove 70 35 but can be moved into communication therewith by forward movement of the valve member 50 relative to the piston 40, that is, by taking up a portion of the lost-motion between these members. The rib 67 is not as wide as the groove 40 70 so that when a portion of the lost-motion between the valve member and piston has been taken up, the groove 65, and hence the hollow 51, is connected not only with the chamber 75 rearward of the piston, but also through the 45 groove 66 and the holes 76 with the chamber 35 forward of the piston. Hence, oil entering the inlet 20 and flowing into the hollow 51 when the piston is in its fully retracted position as shown in Figure 1 but the valve member 50 is partly advanced as shown in Figure 5, flows partly through the openings 61 directly into the chamber 35, partly into the chamber 75 through the holes 70, and partly through the grooves 66 and the holes 76 into the chamber 35. Thus more or less 50 pressure is built up in the chamber 75 according to the relative size of the clearance on either side of the rib 67. As soon as there is any forward movement on the part of the piston 40, the groove 60 is closed by the wall of the casing 55 60 tension 31 so that direct communication between the inlet and outlet through this groove is thereafter cut off until the piston has resumed its normal, fully retracted position. When the groove 60 has been closed by a small forward 65 movement of the piston, or by sufficient relative movement by the valve member 50 to take up all the lost-motion between the valve member and the piston, whereby the forward end face 80 of the valve member 50 engages an annular rib 81 70 within the stem 46, all the oil entering the chamber 36 must flow through the holes 71 and 76 if only a portion of the lost-motion has been taken up, or through the holes 71 alone if all of the lost-motion has been taken up. Thus forward movement of the valve member 50 sufficient 75 to take up all the lost-motion between it and the piston 40 directs the entire flow of the oil entering the inlet 20 into the pressure chamber 75 where the pressure acts against the rear face of the piston 40, this rear face having an area of considerable magnitude compared with the end area of the stem 46 and the cross-sectional area of the valve 50 against which the oil presses in the opposite direction. As long as the lost motion between the valve member 50 and the piston 10 40 is completely taken up, the full pressure of the oil is exerted against the rear face of the piston, thus maintaining a maximum forward drag on the brake rod 44. When pressure on the brake 15 pedal lever 53 is removed, the spring 57 together with oil pressure acting rearwardly against the valve 50, pushes the valve member 50 rearwardly so that further flow through the holes 68 and the groove 65 is completely cut off. The oil pressure in the chamber 75 is relieved through the holes 20 71, the groove 66, and the holes 76, into the chamber 35 and out through the discharge outlet 21. Maximum oil pressure however, is still present in the chamber 36 and is exerted against the forward end of the stem 46 and against the valve 25 30 member 50, this pressure tending to move both members rearwardly. Thus there is a positive rapid return movement of the brake pedal when the pedal has been released by the operator, this return movement being caused by pressure 35 in the chamber 36. As the cross sectional area of this chamber is small compared to the pressure area on the piston 40, the return movement is more rapid than the working movement for a given rate of flow of oil. As soon as the piston 40 and valve member 50 have reached their extreme 40 retracted positions, the groove 60 opens into the chamber 35 and again provides for a direct flow from the inlet 20 to the outlet 21. In order to limit the maximum braking force to be applied 45 by means of the motor, a suitable by-pass 85 is provided between the inlet 20 and the outlet 21, a spring loaded relief valve 86 being connected in this by-pass to relieve any excess pressures above a predetermined maximum which may occur in the inlet 20. The valve 86, as shown, is pressed 50 against its seat as by a spring 87, the physical characteristics of which determine the maximum pressure. A ball check 88 may be provided within the valve 86, this check being held on its seat as 55 by a light spring 89. Thus, if pressure in the discharge 21 should exceed pressure in the inlet 20, as when the brakes are applied when no power fluid is being supplied, this excess in the discharge 21 is at once relieved past the check 60 valve 88.

The piston 40 is also provided with a check valve in the form of an annular plate 90 closing a circular series of holes 91 of suitable size sufficient to permit a relatively large flow of oil from 65 the chamber 35 into the chamber 75 when the piston is moved forwardly. The plate 90 is resiliently held in place as by a number of spring washers 92 on screws 93. Thus if the pump 12 is being driven slowly so that there is insufficient 70 flow of oil to fill the chamber 75 as rapidly as it expands with a quick forward movement of the piston 40, suction in the chamber 75 which might result from such rapid forward movement of the piston is easily relieved by flow of oil through the 75 openings 91 from the chamber 93.

In the upper portion of the casing 30 is an air relief passage 95 opening into the chamber 75 and 35 when the piston is in its fully retracted position. Thus when oil under pressure is first di- 75

rected into the chamber 15 any bubble which may have formed at the uppermost end thereof is quickly discharged through the vent 95 and is swept into the discharge 21, the vent 95 soon 5 thereafter being closed by forward movement of the piston.

From the foregoing description of certain embodiments of this invention, it should be evident to those skilled in the art that various changes 10 and modifications might be made therein without departing from its spirit or scope as defined by the appended claims.

I claim:

1. Mechanism of the class described, comprising a casing having a main chamber with a reduced extension at the forward end thereof, a piston reciprocable in said main chamber forwardly on a working stroke and rearwardly on a return stroke, said piston having a hollow stem 20 extending forwardly and slidably fitted in said chamber extension, a manually operable valve element within said stem with a lost-motion connection thereto, a fluid supply inlet at the forward end of said chamber extension, and a fluid 25 discharge outlet at the forward end of said main chamber, said piston and element having valve openings cooperating to afford free passage of power fluid from the inlet to the outlet only when the piston and element are both at their extreme 30 rearward position, and to direct power fluid against the rear face of the piston when said lost-motion is taken up.

2. Mechanism of the class described, comprising a casing having a main chamber with a reduced extension at its forward end, a piston 35 slidable in said main chamber and having a hollow stem slidably fitted in said extension, and a manually operable element slidably fitted within said stem, said piston and element normally 40 being in their extreme rearward position, a fluid inlet at the forward end of said extension, a fluid outlet at the forward end of said main chamber, said stem having openings through its wall normally providing direct passage for fluid from said 45 extension to the forward portion of said main chamber, said piston and element also having openings cooperating upon take-up of said lost-motion to direct fluid against the rear face of said piston.

3. Mechanism of the class described, comprising a power-actuated member having a forward working stroke from a normal position of rest and a rearward return stroke, said member having front and rear opposed faces of substantially 50 equal area and an additional front face of lesser area, all said faces being adapted to be pressed

by power fluid employed for the actuation of the mechanism, means including a manually operable control element having a lost-motion connection with said member for balancing fluid pressure against said opposed faces when said element is in normal position relative to said member and the member is in its normal position and for directing power fluid against the additional front face only when the element is in its normal position relative to said member but the member is in 10 a forward position.

4. Mechanism of the class described, comprising a casing with an inlet and an outlet, a reciprocable fluid power actuatable member slidable in said casing from and to a normal position of 15 rest, a control element having a lost-motion connection with said member and cooperating therewith to direct power fluid against surfaces of said member to produce follow-up movement, said member having a passage connecting said inlet 20 and outlet when the member is in its normal position and adapted to be closed by said casing whenever said member is displaced from its normal position.

5. Mechanism of the class described, comprising a casing having a main chamber therein and a forward chamber of lesser diameter opening into said main chamber, an inlet duct opening into the forward end of said forward chamber, an outlet duct opening into the forward end of 30 said main chamber, a piston slidably fitted in said main chamber and provided with an extension 35 slidably fitted in said forward chamber, and a control element movable with said piston and capable of limited movement relative thereto to direct power fluid entering said inlet against the rear face of said piston.

6. Mechanism of the class described, comprising a casing having a main chamber and a forward chamber of lesser diameter opening thereinto, an inlet duct opening into the forward end of said forward chamber, an outlet duct opening into the forward end of said main chamber, a piston 40 slidably fitted in said main chamber, said piston having a hollow open-ended extension 45 slidably fitted in said forward chamber, said extension having a passage through its wall opening into said main chamber when the piston is in its rearmost position and cut off from the main chamber when the piston and extension move forwardly, and a valve element having a lost-motion connection with said piston and adapted to cooperate therewith to direct power fluid from said inlet duct against the rear face of said piston.
